UNITED STATES PATENT OFFICE.

MILTON J. SHIMER, OF FREEMANSBURG, PENNSYLVANIA.

SAD-IRON.

SPECIFICATION forming part of Letters Patent No. 353,976, dated December 7, 1886.

Application filed June 24, 1886. Serial No. 206,148. (Model.)

To all whom it may concern:

Be it known that I, MILTON J. SHIMER, a citizen of the United States of America, residing at Freemansburg, in the county of 5 Northampton and State of Pennsylvania, have invented a new and useful Sad-Iron, of which the following is a specification.

My invention has relation to improvements in sad irons, and the object is to simplify and 10 improve the construction of existing implements of the class. This I accomplish by simplifying and cheapening the construction of the iron in that part adapted to receive the detachable handle, which may be readily connected to the iron and as readily detached.

I have fully illustrated my invention in the accompanying drawings, forming a part of this specification, wherein—

Figure 1 is a perspective view of the iron 20 and handle. Fig. 2 is a central vertical longitudinal view thereof; and Fig. 3 is a bottom view of the base-piece of the handle, showing the annular flange and the position of the latch, the ends of the base-piece being broken off.

Like parts in the drawings are designated by similar notations of reference.

Reference being had to the drawings, the letter A designates the iron. This may be cast in one piece, and have formed in the middle 30 a socket, 1, formed with an annular shoulder projecting inwardly over the sides, as seen at 2; or the iron may consist of the main or base part, cast with a pit or socket, and then have a plate secured thereon, with a hole in the middle of less diameter than the socket in 35 the body of the iron, as indicated in Fig. 2, the purpose being to provide a socket with the edges overhanging, to serve as a seat for the catch of the latch pivoted on the handle to set under. On the upper face of the iron, at the 40 forward end, are formed raised ribs 3, which are arranged to rest against the sides of the handle when put in position, and prevent it from turning out of its proper position on the iron.

The letter B designates the handle. This is of cast metal, or may be made of malleable iron struck into the shape shown, and consists of the base-piece 4, uprights 5, and hand-grasp 50 6. The base-piece has an annular depending flange, 7, formed in the middle, to set within

the aperture of the socket in the iron, and also at the middle has the side extensions, 8, which serve to keep the handle steady and in a vertical position when attached to the iron. An 55 aperture, 9, is formed in the base-piece, and the flange 7 is cut away correspondingly to receive the catch of the latch. The uprights 5 of the handle have apertures in their upper ends, through which screws 10 are projected 60 into the wooden hand-grasp 6, and on the inner face of each upright are formed ribs 11, which keep the handle from turning, since when the screws are turned into the handle these ribs are forced into the wood, and thus 65 hold the hand-grasp in a fixed position.

The letter C designates the latch. This is held in bearings 12, formed on the base-plate of the handle, as shown, and has the lever-handle a extended forward, to be carried out 70 of the way of the hand, and so as to be readily within the reach of the thumb of the hand holding the handle. The lower end of the latch is formed with a catch, 13, which sets down through the aperture in the base-piece 75 of the handle, formed for that purpose, and arranged to set with the lip of the catch under the overhanging edge of the socket in the iron. On the back of the catch, to set above the base-piece of the handle, is formed a projection, 14, 80 on which the free end of a spring, 15, secured on the base-piece at 16, bears.

The handle is attached to any iron provided with a suitable socket by forcing it therein, or by pressing back the catch, when the spring 85 will throw the hook or catch under the overhanging edge of the socket and hold the parts in connection; and to disconnect the handle the end of the lever of the catch is drawn from under the edge of the socket, when it may be 90 lifted off.

It will be seen from the foregoing description that I provide a handle which may be very conveniently attached and detached. The depending annular flange sets the handle 95 to the iron, the extended side pieces of the base-piece prevent the handle from slipping sidewise, and the ribs at the end of the iron keep the handle from turning in the socket.

What I claim, and desire to secure by Letters Patent, is—

1. The sad-iron handle B, consisting of the

base-piece 4, having side extensions, 8, and formed with the depending annular flange 7, end supports having ribs 11 on their inner face, and a hand grasp secured between the 5 end supports, and the latch C, having the extended lever-handle 12 and catch 13, formed with the projection 14 on its back, and the spring 15 to bear down on the latch, substantially as described, and for the purpose stated.

10 2. The combination of the sad-iron A, having raised ribs 3 to set against the handle, and formed with a socket, 1, having overhanging edges, with the detachable handle B, the base-piece 4 of which is formed with side exten-

sions, 8, and a depending annular flange, 7, to 15 set in the socket of the iron, and provided with the pivoted latch C, having the extended lever-handle 12, and catch 13, formed with the projections 14 on its back, and the spring 15 to bear down on the latch, substantially as de- 20 scribed, and for the purpose stated.

In witness whereof I have hereunto set my hand in the presence of two attesting witnesses.

MILTON J. SHIMER.

Attest:

F. M. RAUCH,
IRVIN H. SHIMER.
